(57) **CLAIM**

The ornamental design for a radiator for automotive applications, as shown and described.

DESCRIPTION

FIG. 1 is a front elevation view of a radiator for automotive applications showing our new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a perspective view thereof; and,

FIG. 8 is a front elevation view thereof with an exemplary panel attached.

The broken line showing the rectangular panel that occupies the front surface of the radiator is provided for the purpose of illustrating environmental structure and forms no part of the claimed design.
